ATTACHING CLIP FOR METAL MOLDINGS

William R. Wiley, Detroit, Mich.

Application November 2, 1935, Serial No. 47,999

4 Claims. (Cl. 189—88)

This invention relates to a metallic clip for effecting the attachment of sheet metal beading or molding to a sheet metal panel, as in automobile body and door construction work, and has for its object an improved organization of parts by means of which such molding may be quickly, effectively and accurately positioned on the flat or curved panel. Such parts it is of course desirable to have wholly out of sight in the completed construction, and yet it is equally essential that the attachment be capable of rapid installation and be as permanently firm as though the molding and the metal panel were soldered or otherwise metallurgically integrated. The same principle of the frictionally interlocked engagement of parts of the unitary and slightly resilient clip with the juxtaposed molding strip and supporting panel prevails as to each of the slightly variant embodiments of my invention herein disclosed.

In the drawing:

Figure 1 is a perspective of a molding strip positioned on a panel and with one form of holding clip in position thereon, the latter being shown in phantom.

Figure 2 is a side sectional elevation of that one of the embodiments of my invention which is shown in Figure 1.

Figure 3 is a cross sectional end view taken along the line 3—3 of Figure 2 and looking in the direction of the arrows there shown.

Figure 4 is a side sectional elevation of a molding strip and panel piece, with a slightly modified form of clip shown in relation thereto.

Figure 5 is a cross sectional end view of this modified form, taken along the line 5—5 of Figure 4 and looking in the direction of the arrows there shown.

Figure 6 is a side sectional elevational view of a slightly further modified form of clip shown in relation to a molding strip and panel.

Figure 7 is a cross-sectional end view taken along the line 7—7 of Figure 6, and looking in the direction of the arrows there shown.

Referring first to the form of clip illustrated in Figures 1, 2 and 3, A represents a sheet metal body or door panel, upon which the fixed positioning of the molding B is desired. This molding, it will be noted, has inturned flanges C, and

the panel A is preparatorily apertured, as at D, at suitable intervals, for the engagement of the panel-clinching portions of the several clips therethrough. These clips are stamped out from resilient sheet metal and contoured so that the top portion is roughly semi-circular; from about

the center portion depend the panel-engaging legs or branches E and F, while extending longitudinally on either side therefrom, and similarly curved at their tops, are U-shaped branches G and H. All of these parts are united by the central web J. The curvature and size of this top portion and of the curved branches G and H is slightly greater than the distance between the opposing inturned edges C of the molding piece, but so slightly greater that they can be easily forced therebetween. The resiliency of the metal is such, however, that immediately upon the passage of the curved branches G and H between the moulding edges C, their tips spring slightly outward against the webs of the inturned molding edges C, so that thereafter these curved head portions of the clips are firmly lodged within the dome portion of the molding, though capable of being slid therealong.

The depending legs or branches E and F each preferably have their marginal or lateral edges outwardly bent, as at E' and F', as well as being preferably slightly narrowed in breadth at the points E² and F². These latter points represent the approximate position of the panel A relatively to the clips when the molding is firmly seated against the surface of the panel A. The outwardly turned edges E' and F' of the legs E and F, during their passage through the hole in the panel, have not only frictionally engaged the surrounding metal of the panel A, but have both dug therewith slightly, the panel being of softer metal than the clips, and have in many cases found minute irregularities in the supposedly circular contour of the holes D, so that additional holding or clinching results. As soon, however, as the legs E and F have been driven sufficiently through the hole D the shoulders E² and F² at the top of the flanged edges of these depending portions E and F have slipped under the remote surface of the panel A, and, cooperatively with the edges of the panel holes D, have resulted in a clinching of the clip and its attached molding piece firmly against the outer surface of the panel A, so firmly indeed that it is quite unnecessary that the lower ends of the legs or branches E and F be thereafter bent to positions of parallelism with the plane of the panel A.

The modified form of clip illustrated in Figures 4 to 7 inclusive, similarly an integral resilient stamping, involves the union of the panel-engaging legs or branches M and N at their lower ends, as at O, but the resiliency of the clip web or body as a whole is such that the molding strip's inturned edges C are resiliently and marginally en-

gaged by the top portions P and Q respectively of the legs M and N. As in the case of the form of clip first described, these two portions P and Q (Figures 4 and 5) are normally slightly greater in their spacing apart than the space between the marginal edges C of the molding B, so that after the clip is slightly compressed for their forcing therebetween, they spring sufficiently outward for the slightly flared shoulders P' and 10 Q' to engage against the interior surface of the molding flanges, thus forming an interlock against withdrawal, in the same manner as in the case of the curved branches G and H in the form of clip first described. The outwardly bent edges 15 M' and N' of the leg or branch portions M and N engage frictionally against the metal of the panel surrounding the hole D in the same manner as before, and by the provision of bent portions at the top of the branches S and R these resilient 20 legs or branches when passed to the desired depth or degree will thus anchor themselves in desired elevational relation to the plane of the panel, due to the engagement of these bent portions against the panel metal edges surrounding the 25 hole D.

It will be noted that the head portions P and Q of the clip illustrated in Figures 4 and 5 extend practically to engagement with the top or interior domed surface of the molding clip, the 30 slight space shown thereabove in Figure 4 actually representing the immediate center portion of the space enclosed by the molding strip wall, which, of course, tapers off in each direction from the center, so that its interior surface is engaged 35 thereby in the position of the top portions P and Q illustrated in Figure 5. Such a construction lends itself particularly to the assemblage of the molding strip and panel in which a relatively small aperture is provided in the panel and where 40 the clips are first inserted therein and then the molding strip flanges C are thereafter pressed over the resiliently held heads P and Q. In case, however, an appreciably larger hole is made in the panel than is necessary for the entrance of 45 the resilient legs M and N of the clip therethrough, as shown in Figures 6 and 7 at T, I find it unnecessary to cause the head portions, as V and Y, to be of such height that they will engage the top of the molding strip. The resiliency of the clip's web is, however, such that 50 when the branches X and Z are compressed, the heads V and Y may be passed between the molding strip flanges C and their tips V' and Y' will interlock thereover and hold the head portions 55 of the clip from withdrawal from the interior of the molding strip. The tongues W function in the same manner as the tongues R and S in the form last previously described in interlockingly engaging with their inbent tips W' against the 60 rear or rear inner surface of the panel, thus effecting a resilient draw in the other direction from that exerted by the flared points V' and Y' previously described.

What I claim is:

1. A snap fastener installation comprising a plane surfaced apertured support, a hollow supported member having inturned flanges and a one-piece metal double stud fastener adapted to be snapped into an aperture of said support and the interior of the supported member, the part of said fastener extending beyond the support on the side of the supported member lying wholly within said member and engaging the inturned flanges thereof permitting a flush contact between the plane surface of said support and the flanges of said supported member, said part engaging each of said inturned flanges only at points widely spaced lengthwise of the supported member. 15

2. A snap fastener installation comprising an apertured metal support, and a hollow channel-shaped molding strip having inwardly turned flanged edges, a double-ended fastener of one piece folded metal construction having a yieldable portion inserted in the aperture of said support and snapped into locking engagement with a surface thereof, the remainder of said fastener extending beyond the opposite face of said support being wholly confined within the molding and presenting 20 pairs of independent yieldable portions widely spaced endwise of the molding and snapped into engagement with the molding flanges. 25

3. A snap fastener installation comprising an apertured channel-shaped molding strip having 30 inwardly turned flanged edges, a double ended fastener of one piece folded metal construction having converging portions inserted in the aperture of said support, said converging portions having cam surfaces engaging the under surface 35 of said support at the margin of said aperture whereby said snap fastener is snapped into locking engagement with said support, the remainder of said fastener extending beyond the opposite face of said support, being wholly confined with 40 in the molding and presenting pairs of independently yieldable portions widely spaced endwise of the molding and snapped into engagement with the molding flanges. 45

4. A snap fastener installation comprising an apertured metal support and a hollow channel-shaped molding strip having inwardly turned flanged edges, a double ended fastener of one piece folded metal construction having a yieldable portion inserted in the aperture of said support and snapped into locking engagement with a surface thereof, the remainder of said fastener extending beyond the opposite face of said support and comprising a portion extending longitudinally with respect to said hollow channel-shaped molding strip, said longitudinally extending portion having adjacent each end thereof a pair of downwardly extending snap fastener portions independently yieldable and snapped into engagement with the molding flanges to secure 55 the molding in position with respect to said support. 60
